SHIRT COLLAR

Isaac Marinsky, Providence, R. I., assignor of
one-half to Samuel I. Cohen, Providence, R. I.

Application March 26, 1936, Serial No. 70,965

12 Claims. (Cl. 2—116)

My invention relates to shirt collars.

Certain of the objects of my invention are to dispense with collar points which when present abraid the bosom or curl upwardly; to avoid 5 any outward overlap of the collar whereby the required amount of material as well as the expense of laundering is increased; and to render the usual shirt neck-band superfluous and thus save expense and labor in construction, as well 10 as provide the shirt with a free and unobstructed neck opening whereby neck abrasion is avoided and the area of air circulation is increased.

A further object is to afford an attaching 15 means for the collar flap that will shield the neck from view while permitting free egress of a necktie from within the collar, and without interfering with ingress of air for ventilation.

A still further object is to provide means for 20 strengthening the collar at its points of junction with the upper edges of the front sections of the shirt.

An additional object is to insure that any 25 superficial ornamental pattern upon the front sections of the shirt shall be vertical and continuous with the pattern upon the collar exterior.

Other objects and advantages of the invention 30 will be hereinafter apparent or adverted to.

To the above ends essentially my invention 35 consists in such parts and in such combinations of parts as fall within the scope of the appended claims.

In the accompanying drawings,

Figure 1 is a fragmentary front elevation of a 40 shirt including the neck or collar portion thereof, Figure 2, a rear view of the same.

Figure 3, a fragmentary detail of the same looking outwardly against the inside buttoned front of the collar portion,

Figure 4, a fragmentary front elevation of the 45 shirt including the collar portion, the parts being unbuttoned and distended, and the attaching flap being elevated to disclose a fragmentary showing of a necktie.

Figure 5, a similar elevation of the same with 50 the attaching flap in normal position,

Figure 6, a reverse elevation of the parts shown in Figure 4,

Figures 7 and 8, sections taken on line 7—7 of 55 Figure 1, and line 8—8 of Figure 1 respectively,

Figure 9, an elevation of the parts as shown in Figure 1 with the addition of a necktie, and

Figure 10, a fragmentary rear elevation of a 55 modified form of my invention, the parts being unbuttoned and distended and the band being depressed.

Like reference characters indicate like parts throughout the views.

As shown in the drawings a shirt 15 includes a front 16 and back 17. The front comprises front sections 18 and 19 including a pleat portion 20 upon the margin of the section 18, and the back includes an upper or yoke portion 21 and a lower portion 22.

Integral with the front sections 18 and 19 is an upwardly directed longitudinally curved extension 24 terminating in downwardly diverging end edges 26 and 27 forming acute angles with relation to the top edges 28 and 29 of the shirt sections 18 and 19 and affording an opening 30 to admit an upwardly projecting attaching ear 15 32 integral with the pleat portion 20 of the front section 18, and carrying a button 34 upon its front. The shirt front sections 19 and 18 are provided respectively with the usual shirt buttons and button holes respectively, the uppermost 20 of these, 36 and 37 only, being herein shown.

An inner reinforcing strip 39, conforming in size and shape to the extension 24 is fixed to the latter, and has upon the lower portions of its ends angularly directed offset tabs 41 and 42 25 stitched to the upper margins of the sections 18 and 19 respectively and disposed transversely thereto. The extension 24 and strip 39 together constitute the outer member of the collar, represented in a general manner by the reference 30 numeral 44. The extension and strip are connected in their end margins by lines 45 of holding stitching, parallel with the end edges of the collar member, as indicated in Figures 4 and 6, wherein also is indicated a line 47 of holding 35 stitching which connects the lower edge of the strip 39 with the extension and with the upper edge of the yoke 21, intersects the lower portions of the lines 45, and is curved downwardly at its ends, as at 48, to form areas 49 simulating or suggesting the appearance of actual collar points. If it is desired to more conspicuously indicate or emphasize the simulation of a folded over, external flap, or cape type, of shirt collar the needle and thread of the stitching machine may be 40 run over the lines 45 and 47 a second time, thus superposing a second series of stitches upon the first series.

An attaching flap 51, as shown in Figure 7, is composed of two thicknesses of material 52 and 53 flexibly attached at their top edges to the inwardly folded top edges of the layers 24 and 39 of the outer collar member 44 by the line of stitching 54 extending peripherally of the band. This stitching also engages the ends of trans- 55

versely disposed straps 55 upon the face of the member 51 adjacent the collar member. The straps are adapted to slidably retain the band 56 of a tie or scarf. The ends of the member 51 are 5 extended to form projecting portions 58 beyond the collar member and provided with button holes 59. The portions 58 mutually overlap upon the front of the attaching ear 32 when the parts are in wearing position with the button 34 engaged therewith through the button holes 59. In Figure 9 is shown a knot 61 formed from the tie band 56.

The modification shown in Figure 10 differs in structure from that already described in that for 15 the single extension 24 of the earlier figures is substituted a similar extension consisting of two pieces 63 and 64. The contiguous ends of these pieces, as at 66, are attached to the reinforcing strip 39 by stitching. This modification is preferable 20 when the shirt material is figured, and particularly when the figure consists of stripes 68 or other designs comprising parallel figures.

It will be observed that the outer member 44 of the collar is integral at its bottom portion with 25 the front sections 18 and 19 of the shirt, thus avoiding any outwardly folded or overlapping collar portion and thus expense of material and laundering is diminished. The consequent absence of collar points prevents the necessity of 30 locking the points against movement by sewing them to the shirt front, or leaving them to curl or abraid the shirt front.

The integral relation of the member 44 at its bottom with the shirt renders a back collar button unnecessary, and consequently permits dispensing with a neck-band with consequent economy and comfort.

The reinforcing strip 39 stiffens the extension 24, while its terminal tab portions 41 and 42 40 strengthen the garment at the corners formed by the junction of the end edges 26 and 27 of the extension with the adjacent horizontal edges 28 and 29 of the front sections 18 and 19 respectively.

45 By reference particularly to Figures 8 and 9 it will be apparent that while the attaching ear 32 forms a shield against visibility of the neck from the front, there is ample space for the admission of air from outside to the inside of the collar 50 around the lateral edges of the ear.

The particular constructions herein shown may be variously changed and modified without departing from the spirit of my invention or sacrificing the advantages thereof, and as the 55 disclosures herein are illustrative only; my invention is not limited thereto except as defined by the appended claims.

I claim:—

1. In an article of the character described, a 60 shirt having an integral upwardly projecting part forming the outer portion of a collar member, said shirt and said outer portion being one continuous piece of fabric, a depending flap upon the upper portion of the collar member including extended mutually overlapping end portions provided with button holes, and a button carried by the shirt engageable with the flap through the openings.

2. In an article of the character described, a 70 shirt having an integral upwardly projecting part forming the outer portion of a collar member, said shirt and said other portion being one continuous piece of fabric, said outer collar member including an inwardly directed top edge, a depending attaching flap attached to said edge and

including extended interlapping end portions, an upwardly projecting ear upon the shirt, and means upon the ear for detachably engaging the overlapping end portions of the flap.

3. In an article of the character described, a 5 shirt having an integral upwardly projecting part forming the outer portion of a collar member, said shirt and said outer portion being one continuous piece of fabric, said outer collar member terminating in end edges extending downwardly to 10 the top of the shirt, a vertical ear upon the top of the shirt extending intermediate the end edges, and a depending flap flexibly attached at its top to the collar member including overlapping end portions detachably engaging the ear. 15

4. In an article of the character described, a shirt, an outer collar member integral at its bottom with the shirt and terminating laterally in diverging downwardly extending edges defining a triangular opening, said shirt including front 20 sections, a vertical ear upon one section extending into the opening, a depending flap engaged at its top to the upper portion of the collar member and detachably connected with the ear, and lateral tabs carried by the collar member attached 25 to the upper margins of the front sections.

5. In an article of the character described, an outer collar member integral at its bottom with the shirt, a depending flap attached at its top to the upper portion of the collar member and including extended mutually overlapping portions provided with button holes, a plurality of guide strips upon the side of the flap adjacent the collar member adapted to receive a tie band, the shirt having a portion extending upwardly to 35 form a projecting ear, and a button upon the ear engageable with the flap through the button holes.

6. In an article of the character described, a shirt and an outer collar member formed of a 40 continuous piece of fabric, said outer collar member comprising an upright extension, and an inner reinforcing strip fixed to the extension, a depending flap attached at its top to the upper portions of the extension and strip. 45

7. In an article of the character described, a shirt including front sections, an upright extension integral at its bottom with the front sections and terminating in downwardly extending edges defining an opening between the ends of 50 the extension, a vertical ear upon one section extending into the opening, an inner reinforcing strip fixed to the extension, angularly directed tabs upon the ends of the reinforcing strip attached to the upper margins of the front sections, 55 and a flap engaged at its top to the upper portions of the extension and strip and detachably connected to the ear.

8. In an article of the character described, a shirt, an upright extension integral at its bottom 60 with the shirt, and having downwardly directed edges upon its ends, an attaching ear upon the shirt intermediate said edges, an inner reinforcing strip conforming substantially in shape and dimensions with the extension, lines of holding 65 stitches parallel with said edges connecting the end portions of the extension and strip, a line of holding stitches intersecting the lower portions of the first lines and connecting the lower edge of the strip with the extension, said lines simulating the appearance of collar points, and a flap connected by a line of stitches along its top to the upper portion of the extension, and detachably connected to the ear. 70

9. In an article of the character described, a 75

shirt including front sections, an outer collar member integral at its bottom with the sections and vertically bifurcated intermediate its end edges, said end edges defining an opening, a vertical ear upon one section extending into the opening, an inner reinforcing strip conforming substantially in shape and dimensions with the bifurcated extension and fixed thereto with lines of stitching, and a flap engaged at its top to the upper portions of the extension and strip and detachably connected with the ear.

10. In a shirt construction, a shirt body comprising two separable parts, an outer collar member comprising an outer and inner portion, said outer portion extending upwardly from said shirt parts and said inner portion freely depending from said outer portion, the ends of said inner portion having securing members, and an ear extending from the top of one shirt part and adapted to be positioned behind said members.

11. In a shirt construction, a shirt body comprising two separable parts, an outer collar member comprising an outer and inner portion, said

outer portion extending upwardly from said shirt parts and said inner portion freely depending from said outer portion, the ends of said inner portion having securing members, and an ear extending from the top of one shirt part and adapted to be positioned behind said members, said ear having an attaching button secured thereto, and said extensions having button hole openings for detachably securing said members to said ear.

12. In an article of the character described, a shirt having an integral upwardly projecting part extending to the neck line and forming the outer portion of a collar simulating member, and an attaching flap depending inside the shirt from the upper edge of said outer portion and forming the band portion of said collar member, said projecting part terminating in free edges defining the ends of said collar simulating member whereby the shirt and the outer portion of the collar member are formed of a continuous piece of fabric without a separation edge therebetween.

ISAAC MARINSKY.
